STANCHION HALTER

Filed July 2, 1928

Patented Sept. 3, 1929.

1,727,290

UNITED STATES PATENT OFFICE.

GEORGE A. JONES, OF SEDRO WOOLLEY, WASHINGTON.

STANCHION HALTER.

Application filed July 2, 1928. Serial No. 289,874.

This invention relates to stanchion or head stall halters for cattle and is more particularly concerned with a portable halter for use in holding the heads of cattle rigidly in their head stanchions for the performance of any necessary operation thereon, such as dehorning.

An object of the invention is the provision of a stanchion halter having means for positively preventing movement of the animal's head in the stanchion, providing the necessary rigidity for operations on the head, and permitting these operations to be performed in the animal's stall. An important feature of the invention contributing to this end is the provision in connection with a neck and head bar having neck and jaw encircling elements and a front downward pressure applying handle, of a transverse bar adjustably anchoring to the neck bar and having means of anchoring engagement with the stanchion. This transverse or cross bar effectively prevents forward movement of the animal when downward pressure is applied to the handle, forcing the nose down between the stanchions.

This and other features and advantages of the invention will be more clearly apparent from the following detailed specification which is to be read in conjunction with the accompanying drawings forming part thereof, and in which:

Figure 1 is a perspective view of the device of the present invention as applied to the head of an animal in the head stanchion of its stall, the structure of the stall being omitted for the sake of clearness.

Figure 2 is a perspective view of the halter, detached.

Figure 3 is a transverse sectional view on an enlarged scale through the neck portion of the angled bar showing the mounting of the stanchion engaging cross bar thereon, the section being taken on line 3—3 of Figure 2.

Figure 4 is a fragmentary longitudinal section on an enlarged scale through said angle and cross bars, taken on line 4—4 of Figure 2.

In Figure 1 the two spaced uprights 1 and 2 of the head stanchion of the animal's stall are shown separately from the stall itself for the purpose of illustrating the application of the present invention and its relation, in operation, to the stall stanchions between which the head of the cattle is held thereby.

The halter itself comprises an angled bar having a rear portion 3 overlying the neck and serrated on its under face, and a front

portion 4 overlying the head including the nose. Intermediate of its ends approximately at the junction of its angled sides, the bar is provided with an eye 5 through which is 60 looped a chain 6 or other attaching element by which this portion of the bar is suitably connected to and supported from the stanchion. At the lower extremity of its front or head engaging end, a removable pressure applying handle 7 has a metal socket hingedly connected to the lower end of the bar and extending outwardly therefrom at an angle adjustably variable through a chain 8 affixed at one end to an eye bolt 20 threaded into the 65 socket of the handle and having its other end adjustably inserted over a hook bolt 9 threaded into the front portion 4 of the angled bar.

Adjacent to the lower end of the front or head portion of the angled bar it carries on its 70 under face a curved nose piece forming part of a jaw encircling strap element 11 and which carries a threaded stud 110 insertible through and clamping in a selected one of a plurality of holes 10 in the lower end of bar portion 4 75 to adapt the strap element to the size of head.

The rear or neck portion 3 of the bar has one edge split to form a V-shaped retaining notch 12. A throat-embracing strap element, 80 in the form of a chain 13, extends from the edge opposite to this notch, and is intended to embrace the neck of the animal and be inserted through the notch 12 and retained by its edges.

Mounted on the neck portion 3 of the angled bar for adjustment longitudinally thereon to engage and anchor to the stanchion bars 1, 2 is a transversely extending or cross bar 14 having ends 15 spaced by a central channelled portion 16 of an internal cross section 90 to slide longitudinally on the neck portion 3 with its internal face, which lies in confronting relation to the serrated under face of the bar portion 3, similarly serrated to engage therewith as shown in Figure 4. Stanchions piercing elements in the form of pointed projections 17 extend from the opposite end portions 15 of the cross bar to engage the stanchion and anchor the cross bar thereto. The upper face of the channelled portion 95 16 of this bar is slotted and formed with upstanding spaced ears 18 between which is pivotally mounted the clamping cam 19 having a handle extension 20.

The described halter is applied to the neck 110 and head of an animal whose head is inserted in the head stanchions 1, 2 of its stall by

first applying and fastening the nose and jaw embracing strap elements 13 and 11, respectively; and then moving the cross bar 14 forwardly to bring its projections 17 into piercing engagement with the stanchions 1, 2, and 5 clamping the cross bar on the angled bar through cam 19, 20, thereby preventing upward, downward and forward movement of the head in the stanchion with the animal's 10 head held in the proper position for the operation thereon. Downward pressure is now applied through the handle and will hold the head down at the proper angle for the operation to be performed, such, for example, as 15 dehorning. Where the space between the stanchion and an opposite stall is so narrow as to preclude the use of the handle 7, it may be detached from its socket and a rope inserted through a ring 21 mounted on the socket 20 and snubbed to the stanchion to apply the necessary downward pressure. It will be seen, therefore, that the head, once adjusted as described, is firmly held for the dehorning or other operation thereon, and that the described halter construction permits this 25 operation to be performed in the animal's own stall, assuming that its head stanchions are rigid, thereby making it unnecessary for the veterinary surgeon or operator to provide 30 and carry a special stanchion and dispensing with the attendant labor of mounting and securing the same rigidly. Such operations, also, are more safely performed with the animal confined against body movement by 35 the walls of its stall so that the halter has this additional advantage in use.

While the specific construction described and illustrated represents a preferred form of construction, it is intended as illustrative rather than restrictive of the invention. It 40 will, therefore, be understood that structural changes and adaptations to conditions of use and facilities of manufacture are contemplated within the spirit of the invention and the 45 scope of the appended claims.

What I claim, therefore, and desire to secure by Letters Patent is:—

1. A stanchion halter comprising an angled bar to overlie the neck and head having neck and jaw encircling strap elements attached thereto, a pressure applying arm adjustably connected to and extending from the nose end of said bar, and a stanchion engaging member adjustably mounted on the neck end of said bar having means to anchor said member and bar to the stanchion.

2. A stanchion halter comprising an angled bar having neck and jaw encircling strap elements attached thereto, a transversely extending bar slidably mounted on the neck portion of said angled bar and having means thereon to engage and anchor the bar to the stanchion, means to clamp said transverse bar to the angled bar with the former anchored 60 to the stanchion, means to support said angled 65

bar intermediate of its ends from the stanchion, and a pressure applying arm secured to and extending outwardly from the outer end of the angled bar.

3. A stanchion halter comprising an angled bar to overlie the neck and head having neck and jaw encircling strap elements attached thereto and a pressure applying handle secured to and extending outwardly from the front end of the bar, a transverse bar mounted 70 on the neck end of the angled bar for longitudinal sliding movement thereon and having stanchion piercing projections to engage and anchor the bar to the stanchion, and means for clamping said transverse bar to the angled 75 bar in adjusted stanchion anchored position 80 thereon.

4. A stanchion halter comprising an angled bar to overlie the neck and head having neck and jaw encircling strap elements attached 85 thereto and having the under face of its neck portion serrated and having means extending from an intermediate point to anchor said point of the bar to the stanchion, a pressure applying handle attached to and extending outwardly from the front end of said bar, a cross bar having an intermediate channeled portion encircling and sliding over the neck portion of the angled bar and provided with confronting serrations thereon, and having 90 stanchion piercing projections to engage and anchor the cross bar thereto, and a cam mounted on said channeled portion to overlie an opening therein to engage the underlying neck portion of the angled bar to press its serrations into clamping engagement with the confronting serrations of said channeled portion with said cross bar anchored to the stanchion.

5. A stanchion halter comprising an angled bar to overlie the neck and head having neck and jaw encircling strap elements attached thereto and a socket member adjustably hinged to the lower front end of said angled bar and removably seating one end of a pressure applying handle extending outwardly 105 from the front end of the bar, a transverse bar mounted on the neck end of the angled bar for longitudinal sliding movement thereon and having stanchion piercing projections to engage and anchor the bar to the stanchion, and means for clamping said transverse bar to the angled bar in adjusted stanchion anchored position 110 thereon.

6. A stanchion halter comprising an angled bar to overlie the neck and head having neck and jaw encircling strap elements attached thereto, a stanchion engaging member adjustably mounted on the neck end of said bar having means to anchor said member and bar to the stanchion, a socket member hinged 115 to and angularly adjustable relatively to the front end of the head portion of the bar, a handle removably seating in said socket and a snubbing ring anchored to said socket.

7. A stanchion halter comprising an angled 120

bar to engage the neck and head having neck and jaw-encircling elements connected therewith and having means for engagement with a stanchion to anchor said bar thereto, and
5 a pressure applying arm connected to and extending outwardly from the head engaging portion of said bar.

8. A stanchion halter comprising a neck engaging portion having means of anchorage
10 to a stanchion and having a connected neck

encircling element, a head engaging portion having a connected jaw encircling element, and a pressure applying arm attached to and extending outwardly from said head engaging portion.

Signed at Sedro Woolley in the county of Skagit and State of Washington this 20th day of June A. D. nineteen hundred twenty-eight.
